SHEET OF STATIONERY OR THE LIKE

Eugenie J. Jones, Webster Groves, Mo.

Application October 28, 1948, Serial No. 149,339

Term of patent 14 years

(Cl. D59—14)

To all whom it may concern:

Be it known that the undersigned, Eugenie J. Jones, a citizen of the United States, residing in Webster Groves, St. Louis County, Missouri, has invented a new, original, and ornamental Design for a Sheet of Stationery or the like, of which the following is a specification, reference being had to the accompanying drawing, forming a part thereof.

The figure on the drawing shows a face view of a sheet of stationery showing my new design, the essential features of which reside in the portions in full lines.

I claim:

The ornamental design for a sheet of stationery or the like, substantially as shown and described.

EUGENIE J. JONES.
